UNITED STATES PATENT OFFICE.

GEORGE D. PARKER, OF RIVERSIDE, CALIFORNIA.

FRUIT-DRYING APPARATUS.

995,282.

Specification of Letters Patent. Patented June 13, 1911.

Application filed August 2, 1910. Serial No. 575,103.

To all whom it may concern:

Be it known that I, GEORGE D. PARKER, citizen of the United States, residing at Riverside, in the county of Riverside and 5 State of California, have invented certain new and useful Improvements in Fruit-Drying Apparatus, of which the following is a specification, reference being had therein to the accompanying drawing.

10 This invention relates to apparatus for drying the surface of fruit, usually after washing, before packing the same for shipment, it being highly desirable that the surfaces of oranges, for example should be 15 thoroughly dry before they are packed.

With certain drying apparatus heretofore used, a small body of water is likely to accumulate at the point where the orange is supported, and such a body of water is not 20 readily evaporated within the brief time usually allotted.

The object of this invention is to avoid 25 this and other difficulties and to dry fruit perfectly, certainly, and under all ordinary conditions with great rapidity. With this 30 object in view, the fruit from a washing apparatus is advanced by an absorbent conveyer belt from which the water is squeezed as it passes a certain point delivered to 35 a second absorbent belt which carries it through a chamber wherein it is subjected to the action of drying air and is at intervals rolled from one part of the absorbent belt to another thereby exposing all parts 40 of its surface and all parts of the belt's surface to the action of the air.

In the accompanying drawings, Figure 1 45 is a side sectional elevation of the principal parts of my apparatus. Fig. 2 is a plan 50 view of the same devices, the upper part of an inclosing casing being cut away. Fig. 3 is an enlarged detail sectional view of parts seen also in Fig. 1.

In these figures, A represents a suitable 55 casing forming the walls of a drying chamber, and A' an additional casing inclosing devices for bringing fruit from a washing apparatus not shown.

Fruit from the washing apparatus is carried 60 into the drying chamber through an opening A² by an absorbent belt B from which the water is squeezed by a roller C co-acting with the drum B' around which the belt passes. Within the drying chamber 65 is a preferably upwardly inclined car-

rier belt D mounted upon sprocket wheels E, E' and made up of two like, parallel sprocket chains D' connected at equal short intervals by parallel crossbars D². This belt is encircled by a slack, flexible absorbent 60 belt F of somewhat greater length passing around the sprocket wheels E outside the belt D but at the other end passing around an independent drum F'. The upper fold of the flexible belt rests upon the upper fold 65 of the belt D and preferably extends from side to side of the casing, which like the belt D may be of any desired width. At intervals between the sprocket wheels E, E' are mounted revoluble drums or wheels G each 70 having longitudinal teeth or wings G' which project between the crossbars of the belt D and extend above the plane of the same when the tooth is directly above its axis of rotation, as shown in Fig. 3. Drying 75 air is constantly forced into the chamber by means of a fan H.

Fruit advanced by the belt B passes over a bridge I to the belt F which under its weight sags between the crossbars of the 80 underlying belt D, so that the fruit lies in one or another of a series of transverse trough-like depressions. Water which flows to the lower side of the fruit is largely absorbed by the belt, while the moisture and dampness 85 upon the other parts of the fruit is evaporated by the air blast, which, however, obviously cannot dry the fruit surfaces in contact with the belt. When one of the wheels G is reached, the teeth G' push upward the 90 bottom of the trough in which the fruit lies and roll the latter from this part of the belt, exposing to the air the damp surface of the fruit and the damp portion of the belt. This is repeated as often as may be desired, 95 although but two wheels G are shown. That portion of the belt F extending beyond the belt D is supported by a bridge J and from this portion the fruit passes to an inclined or other conveyer and thence from the apparatus. Usually the fan and sprocket wheel shaft below it are driven by belts, as is also the belt B. Usually the drum F' is not positively driven, and no means for drying or heating the air has been shown, such expedients involving, generally, no novelty. 100

What I claim is:

1. In apparatus of the class described, the combination with an absorbent fruit-supporting conveyer adapted to make contact 110

with each orange, or the like, at its lowest point, of means for rolling the fruit from place to place upon the conveyer during its advance.

5 2. In apparatus of the class described, the combination with a flexible conveyer belt, of a traveling belt support adapted to permit the downward sagging of the belt at intervals by the weight of the fruit thereon, and 10 means for periodically elevating the sagged portions to roll the fruit from the same.

3. The combination with a casing and means for creating an air current therein, of an endless belt within the casing adapted to 15 absorb liquid by contact with the lowest points of the rolling fruit, means for delivering fruit upon the belt and for receiving fruit therefrom at another point, and means for rolling the fruit from place to place 20 upon the belt.

4. The combination with a racklike endless belt, of a flexible absorbent belt having one fold resting upon the fold of the belt first mentioned, means for delivering fruit 25 to be dried upon the second belt, means for periodically rolling the fruit from place to place upon the second belt, and means for

creating an air current over the fruit while upon the belt.

5. The combination with a casing and 30 means for driving air through the same, duplicate pairs of sprocket wheels within the casing, an endless belt carried by said sprocket wheels and comprising parallel chains connected at short intervals by cross-bars, a second, loose, flexible, absorbent belt enveloping the belt first mentioned, toothed drums at intervals engaging the upper fold of the first mentioned belt and adapted to project through the same, lifting the absorbent belt, temporarily, therefrom. 35

6. The combination an absorbent conveyer belt, of a casing inclosing the same, means for creating an air current through the casing, a second absorbent belt arranged to deliver fruit upon the first, and means for 40 pressing water from the second belt at one point. 45

In testimony whereof I affix my signature in presence of two witnesses.

GEORGE D. PARKER.
